UNITED STATES PATENT OFFICE

HARRY G. NORWOOD, OF WASHINGTON, DISTRICT OF COLUMBIA, ASSIGNOR TO
THEODORE F. von DORN, OF NEW YORK, N. Y.

RAILWAY-RAIL ANCHOR

Application filed January 29, 1930. Serial No. 424,297.

This invention relates to a new, novel and improved rail anchor designed to be attached to the base portion of railway track rails, and adapted to engage with stationary parts of the railway road bed for the purpose of preventing longitudinal displacement or creeping of the track rails which is liable to occur during the travel of the heavy rolling stock thereupon.

10 The prime object of the invention is to provide a simple, durable, reliable, practical and novel rail anchor, or anti-creeper, possessing a maximum of strength, which when properly and fixedly applied will effectually resist the creeping of the railway track rail.

Another object of the invention is to so construct my novel rail anchor that any tendency of the track rail to creep will serve 20 to swing the anchor about its fulcrum against the cross-tie, thereby causing the anchor to intensify its gripping and clamping power on the track rail.

A further object of the invention is to 25 provide an improved rail anchor formed from a single piece of high grade spring sheet steel, preferably heat treated steel, which under all conditions will serve to prevent any creeping action of the track rail toward an adjacent cross-tie.

The foregoing and such other objects as may appear from the ensuing description are attained by the construction, location, arrangement and combination of the several 35 parts hereinafter more fully described, illustrated in the accompanying drawings and particularly pointed out in the claims appended hereto, it being understood that slight changes in the precise form, proportions and minor details of construction may be resorted to without departing from the spirit or sacrificing any of the advantages of the invention.

In the accompanying drawings forming a 45 part of this specification it will be seen that:

Figure 1 is a side elevation of the improved device embodying my invention applied to a railway track rail, showing the rail in cross-section and in side elevation a 50 railway cross-tie broken away.

Figure 2 is a plan view of the same showing the track rail and cross-tie broken away.

Figure 3 is a plan showing the blank formation of my improved rail anchor before it is stamped into the form in which it 55 is applied to the track rail.

Figure 4 is a plan showing the formation of the blank when stamped into its proper formation for use, and

Figure 5 is a side elevation of the rail 60 anchor detached from the track rail and showing the formation it is caused to assume when it is ready to be fixedly secured to said rail.

In the embodiment of my invention as 65 illustrated, it will be seen that Fig. 1 shows my improved rail anchor applied to the base portion of a standard track rail 1, the said anchor being designated as an entirety, by the letter A, and is formed from a high 70 grade of spring sheet steel possessing the required thickness and dimensions to furnish a maximum strength, by pressing or stamping the blank sheet in suitable dies and at the upper part of the same at one 75 side thereof is formed an overlapping jaw member 2, while at its opposite side or end portion is formed a clamping or gripping member 3, said members being adapted to tightly grip and clamp the base portion of 80 the track rail at each side thereof, respectively, when the anchor shall have been forcibly and properly applied to said rail in its fixed position for use.

The body portion 4 is so stamped and 85 formed that substantially centrally of the blank it is caused to be folded upon itself and assume substantially the formation such as shown in Figs. 4 and 5 of the drawings from the points 5 to 6, the lowermost ends 90 of said body portion being inclined oppositely from each end of the anchor gradually upwardly and inwardly, while the upper ends of said body portion are oppositely inclined from each point 7 and 7' 95 downwardly and outwardly, as clearly shown in Fig. 5, each side of the body portions 8 and 9, being adapted to rest against and contact with a cross-tie 10, dependent upon which side of the track rail to which 100

the anchor is properly and securely applied, therefore, any tendency of the rail to creep immediately results in the anchor being more intensely gripped and clamped to the rail base, and more forcibly and effectually resists any creeping action thereof.

5 At one end portion of the anchor is formed a right angle flange member 11 which materially serves to strengthen said anchor, as well as to form an extended surface or area for the reception of the blows from a 10 sledge such as are usually employed when forcing the anchor on the track rail into its fixed position.

In applying the anchor to the base of the track rail it is simply necessary to place it 15 by hand on one side of the rail base with its jaw member 2 overlapping the upper inclined surface of the rail base with the lower face of the base of the rail contacting the upper face of the body portion 4, 20 then by driving it endwise from its left hand end, as shown in the drawings, with a suitable sledge, such as is usually employed for like purposes, until the inner face of the clamping member 3 passes the opposite 25 edge of the rail base, when the member 3 will immediately snap upwardly and tightly contact and grip the other side of said rail base, all parts in contact with the rail base being simultaneously under intense 30 gripping and clamping action with said base.

This device may be easily removed or detached from the rail base by striking the upper face of the clamping member 3 downwardly, by the use of a suitable tool, and then drive it off from the right hand end of the anchor, as will be readily understood.

It will be perceived that when the anchor 40 shall have been fixedly secured to the rail base in the manner shown in Figs. 1 and 2 the inclined formations 7 and 7' will be forced downwardly and both the upper and lower faces of the body portion will be 45 forced to assume substantially an even and horizontal plane throughout their entire length, hence the greater the tendency to impart a twisting or canting movement of the anchor by its pressure against the cross-tie, thus intensifying the gripping power 50 to all of the parts of the anchor that are in contact with the rail.

It will be readily observed that by the construction of anchor hereinbefore described 55 that when the anchor has been properly applied to the rail base the body portion 7 and 7' will have an intense gripping contact with the lower face of the rail base and any tendency of the rail to creep imparts a corresponding tendency to rock the 60 anchor about its fulcrum against the tie and that such tendency to rock or cant causes the parts to more intensely grip and clamp the upper and lower surfaces of the rail base as well as one edge or side thereof,

therefore, any tendency of the rail to creep immediately results in the anchor being more intensely gripped and clamped to the rail base, and more forcibly and effectually resists any creeping action thereof.

It will be evident that this particular formation of anchor contributes in greatly strengthening it, thus preventing breakage, springing or dislodgment of the anchors when properly applied in its fixed position.

It will be understood that the anchor may be applied from either side of the track rail, and that it may be easily detached from the rail and repeatedly used, thereby increasing its longevity and usefulness.

Having thus described my invention what I claim and desire to secure by Letters Patent is:

1. A one-piece track rail anchor adapted to be fixedly secured to the rail base, comprising a body portion folded upon itself intermediate its ends, with its lowermost face and its upper face inclined in opposite directions.

2. A one-piece track rail anchor adapted to be fixedly secured to the rail base, comprising a body portion folded upon itself intermediate its ends, said body portion having its lowermost face inclined from each end upwardly and inwardly, and its upper face from a point intermediate its ends downwardly and outwardly in opposite directions.

3. A track rail anchor formed of spring sheet steel formed with a clamping member at each end adapted to engage each side of a rail base, and a body portion formed with an upper and a lower face, said faces being inclined in opposite directions.

4. A railway track rail anchor formed of spring sheet steel with a clamping member at each end portion thereof for clamping each side of a rail base, said body portion being folded upwardly intermediate its ends, and formed with oppositely disposed inclined upper faces and oppositely disposed inclined lower faces.

5. A railway track rail anchor formed with a clamping member at each end portion thereof for clamping each side of a rail base, and a body portion folded centrally and upwardly upon itself, and formed with oppositely disposed inclined upper faces and oppositely disposed inclined lower faces.

6. A railway track rail anchor formed of spring sheet steel with a clamping member at each end portion thereof adapted to engage a rail base, and a body portion bent upon itself centrally and upwardly with its lowermost face inclined from each outer end inwardly and upwardly and its upper face inclined from a point intermediate its
